[57] CLAIM

The ornamental design for an extended range folding leaf sight, substantially as shown and described.

DESCRIPTION

FIG. 1 is a perspective view of the extended range folding leaf sight with a grenade launcher and rifle combination shown in phantom lines for illustrative purposes only;

FIG. 2 is a front elevational view of the leaf sight;

FIG. 3 is a left side view thereof;

FIG. 4 is a right side view thereof;

FIG. 5 is a rear elevational view of the leaf sight;

FIG. 6 is a top plan view thereof; and

FIG. 7 is a bottom view thereof.
